UNITED STATES PATENT OFFICE.

GEORGE A. TIMBLIN, OF LANCASTER, PENNSYLVANIA, ASSIGNOR OF TWO-
THIRDS TO WILLIAM F. TROAST, OF SAME PLACE, AND ESPY A. TIMBLIN,
OF CONNELLSVILLE, PENNSYLVANIA.

DESIGN FOR A FRAME FOR GAS-ENGINES.

SPECIFICATION forming part of Design No. 33,592, dated November 20, 1900.

Application filed July 31, 1900. Serial No. 25,470. Term of patent 7 years.

To all whom it may concern:

Be it known that I, GEORGE A. TIMBLIN, a citizen of the United States, residing at Lancaster, in the county of Lancaster and State 5 of Pennsylvania, have invented and produced a new and original Design for a Frame for Gas-Engines, of which the following is a specification, reference being had to the accompanying drawings, forming a part thereof.

10 Figure 1 is a front view of a frame for a gas-engine, showing my design. Fig. 2 is a rear view; Fig. 3, a view of the right side, and Fig. 4 a view of the left side.

As shown in the drawings, the leading or 15 material features of my design consist of a lower section A flat on the sides, convex in general outline front and back, and having in front a flat surface *a*, a cylindrical interme-

diate section B, located above the section A and of the diameter of the width of said section A, and a cylindrical section D above and of less diameter than cylindrical part B. On the back of section A is a projection E, and on the side of cylindrical section B are horizontally-extending projections *b*, terminating 25 in flat vertical faces.

Having thus described my invention, what I claim as new, and desire to secure by Letters Patent, is—

The design for a frame for gas-engines, as 30 herein shown and described.

GEORGE A. TIMBLIN.
